SAFE CONSTRUCTION

Fredrick J. Bremer, Hamilton, Ohio, assignor to
The Mosler Safe Company, Hamilton, Ohio,
a corporation of New York

Application March 26, 1946, Serial No. 657,229

2 Claims. (Cl. 109—84)

1

This invention relates to a new and improved steel safe structure.

The primary object of this invention is to provide a simple and effective fire resistive covering means for steel safes of the burglar resistive type.

Another object of this invention is to provide an improved fire resistive covering means for steel safes without impairing the burglary-resistive qualities thereof.

Another object is to combine effective fire resistive qualities with burglary-resistive qualities in a safe, with a consequent reduction of hazard affecting the contents of the safe.

Another object of this invention is the attainment of the foregoing advantages at a low cost of manufacture, and with a considerable saving of time and labor in fabrication.

These and other objects and advantages are attained by the means described herein and illustrated in the accompanying drawing, in which:

Fig. 1 is a perspective view of a fire-resistive safe or chest embodying the invention.

Fig. 2 is an enlarged fragmental cross-sectional view taken on line 2—2 of Fig. 1.

Fig. 3 is a plan view of a front wall member including stools by which the exterior cladding material is spaced from the chest or safe body.

The average burglary resistive steel safe, while comparatively fire-resistant, does not afford adequate protection to its contents if subjected to heat of substantial intensity. It is with the purpose of giving added protection to a steel safe that a fire-resistive covering has been added without affecting the beauty or utility of the safe. It should be noted that in the present invention, the insulation against heat has been applied to the outside of the safe, whereas in the past it has been the custom to apply insulation to the inside of the steel body of a safe, thereby greatly reducing the capacity or volume of the safe.

Referring to Fig. 1 of the accompanying drawing, the character 6 indicates a flanged disc fixed to the outside face of a heavy door 21 which is adapted for rotation in a swinging frame 7, the latter including hinge means 8. Attached to the front of the safe are cooperating hinge means 9, to which the frame 7 is pivoted for swinging movement on pins 61. A combination lock dial is indicated by 10 and a handle for rotating the disc 6 and door 21 is indicated by 11. Means for retaining insulating material surrounding the main body of the safe is provided by a covering of suitable fire-resistant panels, preferably of metal and hereinafter referred to as cladding, the elements 12, 13, and 14 being the top, front, and side cladding sheets, respectively. The top 12 and the side cladding panels may be in one piece, with bends formed at the upper corners 71, and at the lower corners 72. The

2

door cladding is indicated by the character 15.

As hereinbefore explained, the outer disc member 6 is rotatively supported in the frame 7, as disclosed by Fig. 2. Attached to the outer disc member 6, by means of a number of screws 20, or by other suitable means, is the main door 21, which has on its periphery a plurality of lugs 22 adapted to interlock behind corresponding lugs 23 in the stationary notched frame 24 when the door is rotated within the frame 7. Locking of the safe is attained by means of a locking bolt 25 which engages a notch 26 in one of the lugs 23. The locking bolt 25 may be actuated by the tumbler mechanism 27 through the spindle 28 and the combination dial 10, or with the use of other means common in the art.

Between the outer disc 6 and the main door 21, which may be of drill-resistant metal, is provided a chamber 29 for the envelopment of a suitable non-combustible insulating material 30. The chamber 29 is formed by the door cladding 15 and a pan-like plate 31 suitably joined at points 32 on the periphery of the plate, as by welding or other means. Appropriate spacing between door cladding 15 and plate 32 is obtained by means of tubular spacers 33, through which the screws 20 may be passed for anchorage in the material of door 21. A safe door thus constructed is both fire-resistant and burglary-resistant, as well as sturdy and attractive.

The main body of the safe, as illustrated by Fig. 2, may be constructed of metal either in one piece, as a casting, or it may comprise a plurality of metal plates, the front plate being indicated by 34, the side plates by 35, and the rear plate by 36, all welded or otherwise joined together. The main body may be of drill resistive metal, although not necessarily so. Similar top and bottom plates, which are not shown on the drawings, complete the inner structure of the safe. Welded or otherwise fixedly attached to front plate 34 and rear plate 36 are a number of stools 37, of suitable thickness and length, which serve as spacers for the cladding sides 14, front 13, top 12, and rear 38. These stools 37 are clearly depicted in Fig. 3, which is a plan view of front plate 34. In addition to the stools 37, the front plate 34 has welded or otherwise attached to it the spacers 39, which serve as rigid supports for the door hinges. These spacers 39, being of the same length as stools 37, are bored and threaded to receive screws 40 which secure the hinge members 9 to the main body of the safe. The number of stools 37 employed may be varied, depending upon the rigidity of the cladding, the size of the safe or chest, and other factors involved.

The front plate 34 has a large aperture 41, tapered in conformity with the taper 42 of the main

door member 21 which it engages when closed and locked. The front cladding plate 13 may be flanged peripherally as at 43, to embrace the side and top cladding plates, and is apertured at the front, the aperture 60 thereof being slightly smaller in diameter than the diameter of the door cladding plate 15, so that when the safe door is closed, the door cladding plate 15 overlaps the front cladding plate 13, thereby effecting a seal between the door and the front wall of the safe.

Surrounding the large aperture 60 in the front cladding 13 is a ring 44, substantially Z-shaped in cross section, which acts as a wall for retaining the insulation 45 between front cladding 13 and front plate 34. The larger flange 46 of ring 44 may be welded or otherwise fixedly attached to the front cladding as at 47, while the smaller or inner flange 48 may be welded upon or detachably secured to the front plate 34, as by means of screws 49. When thus assembled, the wall of ring 44 is tapered to conform to the taper in the pan-like plate 31 of the door.

The top cladding 12, front cladding 13, side cladding 14 and the rear cladding 38 are spaced from the several walls of the main body by the outer ends of the several stools 37 located near the corners of the main body of the safe, said stools being of uniform length. The chamber 50 thus created between the main body of the safe and the cladding is filled, preferably from the bottom before closing, with a suitable insulating material 45 capable of rendering the contents of the finished safe immune to high temperature. As a means of finishing and reinforcing the cladding, the cladding corner flanges 43 and 52 may be overlapped upon and welded or otherwise secured to the cladding sides and top, as shown. A bottom cladding panel may be welded to the flanges 43 and 52, and to the undeturned ends of the side panels 14 after the insulating material has been inserted, thus adding a substantial amount of reinforcing to the cladding. All of the angular flanges mentioned may be welded to produce an integral structure.

The safe described herein is sturdy, attractive, and roomy, in addition to being burglary and fire-resistant. The construction features are conducive to simple and expeditious manufacturing procedure, with a substantial saving of time and labor.

Various details in the structural elements of the assembly are subject to modification within the scope of the claims hereto appended without departing from the spirit of the invention. For instance, the door may be of some form other than circular, with a corresponding alteration of the door jamb or opening at the safe front. The nature of the door bolting and locking means is a matter of immateriality to the invention, as is also the manner in which the door is supported upon the front of the safe.

Although the insulation may be applied in sheet form, it is preferable in the interest of facility of assembly to utilize wet or dry insulating material in flake or granular form, or in some other such form so that it may be poured or packed in place to produce a monolithic structure, without resort to cutting and fitting operations.

In practice, the cladding assembly will preferably be supported upon a floor or other surface with its bottom uppermost, whereupon the inside receptacle comprising the heavy metal walls of the chest may be lowered into the cladding assembly. The various spacers on the inside re-

ceptacle will uniformly space it from the cladding, and then the insulating material preferably in wet form may be poured through the open bottom until the entire inner receptacle is surrounded thereby. As the final step in assembling the structure, a bottom plate may be welded or otherwise fixed over the opening, to securely close the open bottom of the cladding. Upon drying or setting, the insulating material becomes a homogeneous mass which is highly effective for rendering all parts of the safe or chest resistive to fire and heat.

I claim:

1. A fire and burglary resistant chest which comprises a hollow body of hard, drill-resistant metal, said body having a circular door opening in a wall thereof, a hollow shell surrounding the sides and top of the body and spaced therefrom, said shell having a circular door opening in registry with the door opening of the body, spacers holding the shell and the body in spaced relationship, fire-resistant insulating material in the space between the body and the shell, a circular door, said door comprising an inner portion of hard drill-resistant metal adapted to close the door opening of the body, an outer insulation retaining sheet portion adapted to close the opening in the shell, means for holding said inner and outer portions in spaced relationship, and fire resistant insulating material in the space between said portions of the door, a door supporting frame having a bearing opening adapted to register with the openings in the body and shell of the chest, a journal member attached to said door and rotatably mounted in said bearing opening, hinges connected to said door supporting frame and to the body, said hinges supporting the frame and the door for swinging between a closed position and an open position, and cooperating lock members on the door and on the body of the chest for locking and unlocking the door in closed position when the door is turned, the insulation in the space between the portions of the door being of substantially the same thickness as and forming substantially a continuation of the insulation between the body and the shell when the door is closed.

2. A fire and burglary resistant chest in accordance with claim 1 characterized by the fact that the means for spacing the shell and the body of the chest comprises a plurality of stools attached to the body and that the hinges are mounted on hinge supporting stools attached to the body of the chest and extending outwardly therefrom, whereby the weight of the door is supported by the body of the box.
